MEASURING LINE REEL

Kenneth D. Bucklin and Charles A. McCarty, Centerville, Iowa, assignors to Cam-Line, Inc., Centerville, Iowa

Filed Oct. 20, 1971, Ser. No. 191,134

Term of patent 14 years

Int. Cl. D10—04

U.S. Cl. D52—1 R

FIG. 1 is a front elevational view of a measuring line reel showing our new design;

FIG. 2 is a top plan view thereof;

FIG. 3 is a right side elevational view thereof;

FIG. 4 is a left side elevational view thereof;

FIG. 5 is a rear elevational view thereof; and

FIG. 6 is a bottom plan view thereof.

We claim:

The ornamental design for a measuring line reel, substantially as shown and described.
